Fig. 1

In the design embodiment comprising FIGURES 7 and 8 the sides, as well as the top and rear, of the instrument are essentially the same in appearance as the corresponding views of the other design embodiment shown.

The dominant features of the design reside in the portions shown in full lines.

I claim:

The ornamental design for a space condition responsive instrument, substantially as shown and described.
